US00D992138S

(12) **United States Design Patent** (10) **Patent No.:** **US D992,138 S**
(45) **Date of Patent:** **** Jul. 11, 2023**

(54) **MASSAGER**

- (71) Applicant: **Pado, Inc.**, Valencia, CA (US)
- (72) Inventors: **Steven Lee**, Valencia, CA (US);
Alejandro Garfio, Mission Viejo, CA (US)
- (73) Assignee: **Pado, Inc.**, Valencia, CA (US)
- (**) Term: **15 Years**
- (21) Appl. No.: **29/815,003**
- (22) Filed: **Nov. 10, 2021**
- (51) LOC (14) Cl. **24-01**
- (52) U.S. Cl.
USPC **D24/215**
- (58) **Field of Classification Search**

Richter & Hampton LLP

(57) **CLAIM**

The ornamental design for a massager, as shown and described.

DESCRIPTION

FIG. 1 is a front perspective view of a massager, showing our new design.

FIG. 2 is a rear perspective view of the massager of FIG. 1.
FIG. 3 is a right side elevational view of the massager of FIG. 1.

FIG. 4 is a left side elevational view of the massager of FIG. 1.

FIG. 5 is a front elevational view of the massager of FIG. 1.
FIG. 6 is a rear elevational view of the massager of FIG. 1.
FIG. 7 is a top plan view of the massager attachment of FIG. 1; and,

FIG. 8 is a bottom plan view of the massager of FIG. 1.
The broken lines in the drawings are for the purpose of illustrating portions of the massager, which form no part of the claimed design.

1 Claim, 7 Drawing Sheets
